James Riley.

Letters Patent.

The Schedule referred to in these Letters Patent, and making part of the same, containing a description in the words of the said James Riley himself of his improvement in the Manufac-ture of suction hoses for Fire Engines &c.

Before describing my improved suction hose, I will describe the suction hose now in general use, so that the difference between the two, and the advantages of my improvement may be more apparent.

The suction hose now in use is made in the following manner, leather rings of two inches in diameter, or thereabouts, are slipped upon a pole of the same diameter, a wire to each other a spiral and covered with leather. Then, sometimes, a composition of Tar &c is put over the leather, and the whole is covered in an additional covering of leather. The pole is then drawn out, and the hose made by stitching the leather for the equipment of one. This engine is usually made of four pieces, each four feet in length, two of which pieces (when the hose is not in use) are run upon poles, and are suspended upon each side of the engine. This hose, as is manifested from the above description, is inelastic. The improved suction hose which I have invented, and for which I hereby claim a Patent, is made in this manner. A pole of the size of suction hose wanted, is first covered with leather. The pole is then taken out, and a size of wire corresponding to the diameter of the hose intended to be attached to the suction hose is wound on to this pole, after winding on sufficient wire to cover the leather, this spiral wire is slipped off of the pole, and numerous little knots are fastened down to the leather, by a whip stitch from end to end. Then a composition made of India Rubber dissolved in alcohol, is put on, from end to end, to cover the whole of the spiral wire. The leather thus covered with spiral wire and composition,

is then inserted into a ring of leather, which completes the hose. This hose can be made of any length required.

The great advantages, which any improved suction hose possesses over the hose now in use, are, 1st. That it is elastic, and is capable of being easily wound up upon a reel; whereas the common suction hose is inelastic, cannot be wound up, and must be made in short pieces, of about one foot each in length, which pieces must be forced together before commencing operations. This operation of screwing together pieces in cold weather, often occupies a half an hour which is a great loss of time. 2d. The suction hose now in use, is to be drawn, as above mentioned, must be slipped upon poles suspended on each side of the fire engine, which have a curved and increasing appendage to the engines, or must (when not in use) be otherwise disposed of in some manner equally as inconvenient. Whereas any improved suction hose can always remain coiled at one of its extremities to the aperture leading into the interior of the engine, and the hose be twisted around some convenient part of the engine, thus being at all times ready for instantaneous action, by dropping it into the reservoir, without losing any time in screwing it together, it being in one piece. In cold freezing weather, this is a very important advantage.

3d. Coming to the suction, there now in use being temporarily made in such short pieces, not more than two fire engines can conveniently be stationed at one reservoir of water, for suction at one time. I mean such reservoirs as are constructed under ground, in Boston, in the different streets, containing large quantities of water to be used in the extinguishing of fires. Any improved suction hose can be made of any required length, so that any number of engines may be drawing water simultaneously from the same reservoir. The great length of the suction hose admitting them to stand at various distances from the reservoir without interfering with each other. To conclude. I claim

as my invention. This above described improvement in the function
of the air pump, whereby such pump is rendered electric;-
and always remains secured to the fire engine by one of its exterior
fixed work economically in regard about expense, part of the engine
when not in use; and that it may be made of any length which
supersedes the necessity of screwing together, allows it to be put
into operation instantaneously and permits any number of
engines to be drawing water simultaneously from the same
reservoir.
